UNITED STATES PATENT OFFICE.

MICHAEL BARTHOLOMEW RYAN, OF BALDWIN STATION, CONNECTICUT.

CHAIN-LINK.

1,198,060.

Specification of Letters Patent. Patented Sept. 12, 1916.

Application filed June 30, 1914. Serial No. 848,123.

To all whom it may concern:

Be it known that I, MICHAEL B. RYAN, a citizen of the United States, and a resident of Baldwin Station, in the county of New Haven and State of Connecticut, have invented a certain new and useful Improvement in Chain-Links, of which the following is a specification.

The invention relates particularly to improvements in the construction of wire-links for chains shown and described in Letters Patent granted to me April 14, 1914, No. 1,093,209.

The object of the invention is to provide a cheap, strong and durable light weight link for hitching and draft chains, and for such uses where strength combined with light weight is essential or desired.

The invention consists in forming a link 20 of a single strand of metal of uniform diameter, preferably steel wire, and bending it intermediate its ends to provide two loops or eyes of substantially the same diameter and arranged in planes at substantially right angles to each other, and in extending the ends of the metal so that they will engage and overlap one another and to lie against the body portion of the metal at the center of the link, and further in welding the said 30 ends together and to the said body portion of the link so as to provide closed loops or eyes to thus prevent the links when formed into a chain from being detached and the loops from being opened and the consequent 35 parting of the chain when strain is placed thereon.

The invention further consists in the details of construction as will be hereinafter fully described and then claimed.

40 In the accompanying drawing illustrating the invention, in the several figures of which like parts are similarly designated, Figure 1 is a front view of one form of my improved link. Fig. 2 is a side view of the 45 same looking toward the side of the link indicated by the arrow *a*, Fig. 1. Fig. 3 is a rear view of the link. Fig. 4 is a cross section of the link drawn through the central portion thereof on the line *x*—*x* of 50 Fig. 1.

In the construction shown in Figs. 1, 2, 3 and 4, the link is formed from a single strand of metal, preferably steel wire, which is bent intermediate its ends in right-angled directions to form loops or eyes 2 and 3,

of any desired shape, so that the said loops or eyes will lie in planes at substantially right angles to each other, the extreme ends of the metal being extended slightly past the longitudinal center of the link and bent 60 to provide short parallel sections 4 which are arranged to lie against each other and against the substantially straight central section 5 of the link. When the link is thus formed the ends 4 are pressed together and to the straight section 5 of the body portion thereof, and are welded together and to the said body portion 5, into a solid mass, thus providing an endless link of two non-communicating loops or eyes.

It will thus be seen that I provide an exceedingly strong and durable link from less metal than would otherwise be used were the ends bent around the body of the link in order to secure them in position and which consequently enables me to produce a chain at less cost and of greater strength for given weight material than has heretofore been constructed, and by overlapping the ends 70 of the blank and welding them together and to the body of the link I secure a comparatively large welding surface and at the same time avoid making the joint at the wearing surfaces of or in the sides of the loops as in the construction shown in my said Letters 75 Patent No. 1,093,208, and thus reduce the liability of breaking the joint should the chain be twisted and an excessive wrenching strain placed thereon.

What I claim is:—

1. A chain link, constructed of a single strand of metal bent intermediate its ends to provide loops or eyes arranged in planes substantially at right-angles to each other, and having the extreme ends of the metal 95 bent to extend lengthwise of the body of the link so as to lie against each other and against the said body portion, said ends being welded together and to the body of the link.

2. A chain link, constructed of a single strand of metal bent to provide two loops or eyes which are disposed in planes substantially at right-angles to each other, and having the ends of the metal bent so as to lie 105 lengthwise of and engage the body of the link and to overlap and engage each other, said overlapped portions of the ends being welded together and to the body of the link.

3. A chain link, constructed of a single 110

strand of metal bent intermediate its ends to provide two loops or eyes, the extreme ends of the metal being bent so as to engage each other and to lie lengthwise of the body of 5 the link at substantially the central portion thereof, the said ends being welded together and to the body portion of the link.

4. A chain link comprising a blank of wire having its ends welded to and lying

substantially parallel with the central portion, so as to form two opposite eyes.

In testimony whereof I have hereunto set my hand this 24 day of June, A. D. 1914.

MICHAEL BARTHOLOMEW RYAN.
